UNITED STATES PATENT OFFICE.

EDWARD W. McCORMICK, OF NEW YORK, N. Y., ASSIGNOR TO CHARLES HARRISON, OF SAME PLACE.

SELF-CLOSING COCK.

SPECIFICATION forming part of Letters Patent No. 245,737, dated August 16, 1881.

Application filed June 11, 1881. (No model.)

To all whom it may concern:

Be it known that I, EDWARD W. McCORMICK, of the city and State of New York, have invented certain Improvements in Self-Closing Cocks, of which the following is a specification.

My improvements relate to that class of self-closing cocks in which the valve is held upon its seat by the expansive force of a spiral spring, either with the aid of the water-pressure in the pipe or against such pressure, according to the manner in which the valve is arranged.

In the accompanying drawings I have illustrated two methods of applying my invention. In one the water-pressure tends to hold the valve upon its seat, permitting a lighter spring to be used, and in the other, by means of a stiffer spring, the valve is held upon its seat against the pressure of the water.

In the accompanying drawings, illustrating cocks embodying my improvements, Figure 1 is an elevation, partly in vertical section, of what I regard as the preferable form of applying my improvement, in which the water-pressure co-operates with the force of the spring in holding the valve upon its seat. Fig. 2 is a horizontal section of the shell of the cock through the line *x x* on Fig. 1. Fig. 3 is a longitudinal vertical section of the shell of a cock containing my improvement, in which the valve is held upon its seat against the pressure of the water by a more powerful spiral spring. Fig. 4 is a horizontal section thereof, taken through the line *y y* on Fig. 3.

In that modification of my invention represented in Figs. 1 and 2 the shell *A* of the cock is divided into two chambers, the inlet chamber *B*, the upper horizontal extension of which constitutes the valve-chamber *b*, and the outlet chamber *C*, the vertical extension *c* of which is provided at the top with the cap *c'*, which affords the upper bearing for the spindle *D*, by the oscillation of which in either direction the valve *E* is pushed backward from its seat *e*.

The range of oscillation of the spindle is limited by means of a radially-projecting tooth, *d*, which, at either end of its path of oscillatory motion, is arrested by collision with the

stops *c''*, projecting inwardly from the wall of the vertical extension *c* of the outlet-chamber.

The spindle is provided with a fixed collar, *D'*, the upper surface of which bears against a packing-ring introduced between the bottom of the cap and the top of the wall of the spindle-chamber. The lower end, *D''*, of the spindle is stepped in the cylindrical recess *C'*, formed in the bottom of the outlet-chamber.

The valve is provided with a projection, *E'*, which presents a flat bearing for the rocking lever *D''*, by which the valve is operated. This rocking lever may either be a piece affixed transversely to the spindle, or, as represented in the drawings, it may be a flattened portion of the spindle itself.

The valve-stem *E''* is journaled in the recess *e'*, formed in the rear wall of the valve-chamber, and the spiral spring *E''*, surrounding the valve-stem, tends to thrust the valve against its seat.

In the modification represented in Figs. 3 and 4 the shell *G* of the cock is divided into two chambers—the inlet-chamber *H* and the outlet-chamber *I*. In this case the valve *K* is affixed to or formed in one piece with the branches *k k* of the stem *K'*, having its end bearing in the perforated pillar *i*, fastened transversely across the outlet-chamber. On the other end the valve is affixed to the stem *K''*, which has its bearing in the pillar *h*, fastened transversely across the inlet-chamber. An expanding spiral spring, *L*, bears at one end against the pillar *i*, and at the other end against the cross-head *k'*, of the stem *K'*, which connects the branches *k k*, to which the valve *K* is attached.

A vertical extension, *I'*, of the outlet-chamber is provided with the cap *I''*, which affords the upper bearing for the spindle *M*.

At its lower end, *m*, the spindle is stepped in the cylindrical recess *I''*, formed in the bottom of the outlet-chamber. The spindle is inserted through the space between the valve *K* and the cross-head *k'* of the stem *K'*, and is provided with a flattened face to form the rocking lever *M'*, which bears upon the surface of the cross-head *k'*.

As in the other modification of my invention,

the spindle is provided with a fixed collar, M^2 , which bears against a washer introduced between it and the under side of the cap I^2 , and is also provided with the projecting teeth m' 5 m' , which serve to arrest the oscillatory movement of the spindle by striking against stops projecting inwardly from the wall of the vertical extension of the outlet-chamber.

The valve K is held upon its seat K^3 solely 10 by the expansive force of the spiral spring L , which in this case must be strong enough to resist the pressure of the fluid in the inlet-chamber H .

It will be seen that by oscillating the spindle M in either direction the valve K will be withdrawn from its seat, and that upon letting go 15 of the spindle the spiral spring will force the

valve back upon its seat, and at the same time rock the spindle around into its normal position.

I claim as my invention—

In a self-closing cock substantially of the character described, a retracting spring-valve and an oscillating spindle carrying a rocking lever or flattened face for operating such valve, 20 and provided with the radially-projecting tooth d , in combination with the stops c^2 , for limiting the range of oscillation of the spindle, substantially as set forth.

EDWARD W. McCORMICK.
